DESIGN FOR A COMBINATION TOOTHPICK HOLDER AND DIET CHART

Helen M. Hebel, Decatur, Ill.

Application March 27, 1940, Serial No. 91,266

Term of patent 14 years

To all whom it may concern:

Be it known that I, Helen M. Hebel, a citizen of the United States, residing at Decatur, in the county of Macon and State of Illinois, have invented a new, original, and ornamental Design for a Combination Toothpick Holder and Diet Chart, of which the following is a specification, reference being had to the accompanying drawing, forming part thereof, wherein—toothpick holder and diet chart showing my new design, looking from the front and side;

Fig. 2 is a side elevational view thereof;

Fig. 3 is a front elevational view thereof;

Fig. 4 is a rear elevational view thereof; and

Fig. 5 is a top plan view thereof.

I claim:

The ornamental design for a combination toothpick holder and diet chart, as shown.

HELEN M. HEBEL.
